CLAIM

The ornamental design for a frying pan, as shown and described.

DESCRIPTION

FIG. 1 is a top right perspective of a frying pan, according to the present invention.

FIG. 2 is a top left perspective of the frying pan of FIG. 1; FIG. 3 is a bottom left perspective of the frying pan of FIG. 1;

FIG. 4 is a left side elevation view of the frying pan of FIG. 1;

FIG. 5 is a right side elevation view of the frying pan of FIG. 1;

FIG. 6 is a front elevation view of the frying pan of FIG. 1; FIG. 7 is a back elevation view of the frying pan of FIG. 1;

FIG. 8 is a top plan view of the frying pan of FIG. 1; and, FIG. 9 is a bottom plan view of the frying pan of FIG. 1. The broken lines in the drawings depict portions of the frying pan that form no part of the claimed design.

1 Claim, 7 Drawing Sheets
